UNITED STATES PATENT OFFICE.

JOSEPH R. McMAHON, OF GLENDALE, WEST VIRGINIA, ASSIGNOR OF ONE-FOURTH TO HIMSELF, ONE-FOURTH TO J. T. McMAHON, ONE-FOURTH TO R. A. McMAHON, AND ONE-FOURTH TO C. P. McMAHON, ALL OF GLENDALE, WEST VIRGINIA.

MACHINE FOR FORMING SHEET-METAL LATH.

Application filed March 10, 1923. Serial No. 324,114.

To all whom it may concern:

Be it known that I, JOSEPH R. McMAHON, a citizen of the United States of America, and resident of Glendale, county of Marshall, and State of West Virginia, have invented certain new and useful Improvements in Machines for Forming Sheet-Metal Laths, of which the following is a specification.

10 This invention relates broadly to sheet bending mechanisms, and more specifically to a machine for forming sheet-metal lath.

The primary object of the invention is to provide a machine for bending metal sheets 15 to form lath of that type in which a plurality of parallel spaced channels of dovetail form in cross section are provided for the reception of plaster tongues whereby the plaster is interlocked therewith, or keyed 20 thereto.

A further object of the invention is to provide a machine of the character mentioned which is wholly automatic in its operation, being adapted to advance a sheet fed thereto 25 in intermittent steps of a definite length and to form therein the various relatively spaced channels during the intervals in which the sheet remains at rest.

With these and other objects in view, 30 the invention resides in the features of construction, arrangement of parts and combinations of elements which will hereinafter be fully described, reference being herein had to the accompanying drawings, in 35 which—

Figure 1 is an end elevation of the invention;

Fig. 2 is a side elevation of the same;

Fig. 3 is an enlarged sectional elevation 40 of the invention, parts being shown broken away;

Fig. 4 is an enlarged detail view, partially in section and partially in side elevation, illustrating the sheet advancing mechanism;

Fig. 5 is a detail view of the mechanism 45 by which the formed end of the sheet is advanced;

Fig. 6 is a view in cross section illustrating a modified form of thrust pins;

Fig. 7 is a side elevation of the turret;

Figs. 8 and 9 are end and side elevations, respectively, of one of the lower dies;

Figs. 10 and 11 are similar views of a die-carrying slide;

Fig. 12 is a detail sectional elevation 55 showing the upper and lower dies disposed in their cooperative sheet-bending relation;

Fig. 13 is a section on line 13—13, Fig. 12, with the ram removed;

Fig. 14 is a cross section of a modified 60 form of upper die support and ram;

Fig. 15 is a fragmentary elevation of the same;

Fig. 16 is a cross section of a modified 65 form of lower die support;

Fig. 17 is a fragmentary elevation of the same;

Fig. 18 is a perspective view of a partially formed sheet; and—

Fig. 19 is a detail view in top plan of 70 an end portion of the ram and the slideway in which it operates.

Referring to said drawings, 1 indicates the opposite sides of a supporting frame, or housings, which have stationarily mounted on the top thereof the opposite ends of a transversely disposed turret 2 of truncated cone form in cross section, the opposite inclined walls of said turret being inclined at equal angles, approximately forty- 75 five degrees, to the vertical. Located rearward of said turret and in a common horizontal plane with the flat top face of the latter is a table 3 having the front edge thereof located at a suitably spaced distance 80 from the adjacent turret wall; and located forward of said turret and on a somewhat lower plane is a table 4 which has its rear edge spaced from the adjacent turret wall. Said tables 3 and 4, which form beds over 85 which metal sheets to be acted upon are advanced over the turret, are mounted upon stationary supports 5 and 6 which rest upon the housings 1 and which embody transverse walls 5^a and 6^a located parallel to and at 90 a suitably spaced distance from the adjacent walls of the turret to form intermediate guideways 7, the purpose of which will hereinafter be made apparent.

A pair of transversely disposed upper 100 die members 8 are mounted for reciprocation with respect to the flat top face of the turret 2 and are adapted in their lowered position to firmly seat upon that portion of a metal sheet which overlies said top face. Each 105 of said die members has formed in its under face a rabbet 9 presenting an outwardly facing acute angle into which the under-

lying metal of the sheet acted upon is forced by cooperating lower dies 10, as will hereinafter be described.

Said upper dies 8 are rigidly carried on the under sides of the inner or confronting edge portions of a pair of heavy transverse bars or plates 11 which carry upon the opposite ends of their outer edge portions trunnions 12 that are journaled in upright frame members or supports 13 carried by the housings 1. Integral arms 14 carried by the said outer edge portions of said plates 11 have pivotally attached thereto the inner ends of substantially horizontal levers 15 which are pivotally mounted intermediate their ends upon said supports 13 and which have their outer ends pivoted to the lower ends of upright links 16, the links at each side of the machine being connected by a horizontal longitudinally extending bar 17.

The lower dies 10 are removably mounted upon reciprocable slides 18 which are disposed for movement in the guidways 7. Each of said slides has integral lugs 19 on the lower edge thereof adjacent to its ends, and pivoted to said lugs are the upper ends of rods or links 20, adjustable as to length, which are pivoted at their lower ends upon the upper ends of downwardly and inwardly inclined levers 21. Each of said levers 21 is pivotally mounted intermediate its ends upon the adjacent housings 1 and carries upon its lower end a roller 22 which is disposed in seated relation to a cam 23, being yieldingly held in such relation by a retractile coil spring 24 attached at its upper end to the outer end portion of the lever 21 and at its lower end to a fixed member, as a bolt or stud 25, carried by the adjacent housing 1.

The cams 23, located side by side, are carried by a shaft 26 journaled in the lower part of the housings 1, and each thereof is adapted in each revolution to swing the therewith associated lever 21 against the tension of its spring 24 for elevating the attached link 20 and, consequently, the slide 18 supported by the latter, for thrusting the dies 10 upward into cooperative sheet-bending relation to the lowered upper dies 8.

Each of the inclined walls 5^a and 6^a of the supports 5 and 6 carries upon the upper portion of the side facing the adjacent guideway a plate 27 which is inclined at a greater angle to the vertical than the wall to which it is attached, and disposed in underlying seated relation to said plate when the adjacent slide 18 occupies its normal lowered position is a shoulder 28 formed on said slide, said shoulder having an inclination corresponding to that of said plate. Said plate constitutes a deflector which cooperates with said shoulder for thrusting the slide inward toward the adjacent wall of the turret as said slide is elevated. This inward deflec-

tion of the slides occurs gradually during the elevation of the latter into cooperative relation to the upper dies, whereby the bending of the interposed metal sheet about the upper dies is effected without the shearing action which would obviously attend elevating movement of the lower dies in a straight line, or directly toward the beveled edges of said upper dies.

When in their lowered positions, the slides 18 are held in an outwardly thrust position with respect to the walls of the turret by pins 29 which bear thereagainst, said pins being movable through and having their ends projected outward through said walls into seated bearing relation to said slides. The inner ends of said pins rest against a vertically reciprocable block 30 of wedge shape which is supported upon the upper ends of pitmen 31. Each pitman has a short slot 32 in its lower end through which the drive-shaft 26 is directed. A cam 33 fixed on said shaft adjacent to each pitman is disposed in underlying relation to a roller 34 carried by the pitman whereby the latter is maintained in elevated position in which the pins 29 are pressed outward, except during the part of each revolution of the cam in which the lower slides 18 occupy their upwardly thrust positions. It will of course be understood that the cam 33 is so formed and positioned that the block 30 will be raised and lowered in properly timed relation to the movements of the slides.

As is apparent, the dies 8 and 10 are designed to form in metal sheets 35 transverse channels 36 of dovetail form at regularly spaced intervals, as shown in Figs. 12 and 18, for forming metal lath of a character adapted for attaching to the studding of a wall and for having a coating of plaster applied thereto, said channels being designed to receive therein plaster in the form of rib-like locking lugs whereby the coating is retained in place.

The upper dies 8 are normally held in the elevated position shown in Fig. 3 and are actuated to move to lowered seating position with respect to a sheet overlying the top face of the turret 2 by mechanism which includes a transverse ram 37. Said ram, which is disposed for vertically reciprocating movement with the respect to the inner edge portions of the die-carrying plates 11, is designed to be actuated to forcibly depress said plates at proper times to lowered positions in which they seat upon an interposed sheet for cooperating with the lower dies 10. Said ram has its opposite ends mounted on slide blocks 38 which are movable in vertical slideways 39 provided therefor in the supports 13, and said slide blocks have trunnions mounted in the upper ends of upright pitmen 40. Each pitman 40 has a short slot 41 in its lower end through which the

drive shaft 26 is directed and carries thereon suitably located upper and lower rollers 42 and 43 adapted to be alternately engaged by a cam 44 fixed on said shaft whereby said pitman is raised and lowered for effecting elevation and depression of the ram 37. As is obvious, when said ram is lowered, it seats upon and forces the plates 11 downward for firmly seating the dies 8 upon the sheet which overlies the top face of the turret, and when said ram is elevated, it strikes against and raises the overlying bars 17, thus, through the intermediate mechanism hereinbefore described, swinging said plates to the positions in which said dies are elevated.

The metal sheets are advanced over the table 3 to the position in which they are acted upon by the dies, as aforesaid, by means of a set of rolls 45 and 46 which are intermittently actuated, and the shaped end of the sheet is advanced over the table 4 away from said position by intermittently actuated dogs 47, said rolls and dogs being simultaneously actuated. The actuating means for said rolls and said dogs comprises a horizontally disposed bar 48 which is mounted intermediate its ends upon an end portion of the drive shaft 26, having therein a slot or elongated opening 49 through which said shaft extends. Rollers 50 and 51 carried by the bar 48 forward and rearward of said opening 49 are adapted to be alternately engaged by a cam 52 carried by said shaft, whereby said bar is shifted forward and rearward in each revolution of said shaft. Pivotaly attached to the rear end of said bar 48 is the lower end of an upright lever 53 which is pivotally mounted intermediate its ends upon an outstanding arm or post 54 carried by the adjacent housing. The upper end of said lever carries a pivoted pawl 55 which has its free end engaged with a ratchet wheel 56 carried by the neck of the lower roll 46. Thus, as is manifest, rearward shifting movement of said bar 48, effected as described, actuates the pawl 55 through the lever 53 to impart through the ratchet wheel 56 a definite movement whereby is effected the forward rotation of said lower roll throughout a definite part of a revolution for advancing a definite distance a metal sheet received between said roll and the overlying frictionally driven roll 45.

The forward end of the bar 48 likewise has pivoted thereto the lower end of an upright lever 57 which has its upper end fixed to an end of a transverse rock-shaft 58. Said rock-shaft is mounted in the housings and carries thereon at points located slightly outside the path of movement of the sheets a pair of upright arms 59, each of which has pivoted to its upper end a dog 47 adapted to overlie the adjacent edge portion of the sheet. Rearward shifting of the bar

48 thus imparts to said dogs 47, through the intermediate lever 57, rock-shaft 58 and arms 59, a definite forward travel, and, since said dogs seat behind the transverse upright ribs formed in the sheet, they act to thrust forward therewith the shaped end of the sheet producing forward travel of said end simultaneously with the advance effected by the feed rolls. Rollers 61 carried by said dogs 47 rearward of their free ends provide for elevating the dogs as they are retracted over the ribs of the sheet to new positions.

It will of course be understood that the various mechanisms hereinbefore described are arranged to operate at properly timed intervals and in proper sequence for performing their various functions.

In Fig. 6 is illustrated a modified form of pin and pin mounting whereby the slides which carry the lower dies are normally held in outwardly thrust positions, dispensing with the block 30 and its actuating means. In said modified form the pins 29^a have their inner ends resting against spiral compression springs 62 which are interposed between said ends and bolt 63 adjustably mounted in brackets 64 carried on the inner faces of the turret walls.

In the modification illustrated in Figs. 14 and 15, the upper dies 8^a are carried by companion bars 11^a. Said bars are connected by a plurality of horizontally disposed tie rods 65 upon which they are slideable toward and away from each other, said rods carrying compression springs 66 which normally hold said bars in abutting relation. Companion bevels 67 are provided in the inner upper faces of the bars whereby are constituted longitudinally extending channels of V-shape adapted for the reception of the correspondingly shaped under side of the modified form of ram 37^a, said ram being designed to depress the die-carrying bars 11^a to seated position with respect to an underlying metal sheet and, at the same time, to wedge said bars apart for positioning the dies 8^a in their proper operative relation. Upon elevation of the ram, the bars 11^a and, consequently, the dies 8^a, are contracted by the springs 66 from their expanded working position, insuring release of the metal of the sheet shaped about said dies.

In the modification shown in Figs. 16 and 17, a heavy transversely disposed bar-like bed 68 is substituted for the turret 2, the same having formed therein a trough-like channel 69 with correspondingly inclined side walls 70. Disposed for sliding movement against the opposite side walls are slide-bars 18^a which are normally supported by underlying compression springs 71 in positions wherein their upper faces are elevated above the level of the bed 68. Said

bars carry on their upper faces lower die members 10^a which are moved toward each other for cooperating with the upper dies when said bars are forced downward against the tensions of said springs 71, such lowering of said bars being effected by pressure applied thereto through the depression of the upper dies following seating of the latter thereon. As is evident, the structures disclosed in Figs. 14 and 16 are especially well adapted for use in conjunction with each other, in which case the depression of the two sets of dies into cooperating sheet-shaping relation is effected wholly by the lowering force applied through the ram 37^a, such force further inducing relative movement of the upper dies to their separated operating position and inducing movement of the lower dies to their relatively inwardly drawn positions, and said movements being simultaneously effected in such manner that the interposed portion of a sheet is gradually bent into shape without any tendency to produce shearing of the sheet.

Various modifications in the forms and arrangement of some of the parts, other than those herein specifically referred to may obviously be resorted to without departing from the spirit or scope of the appended claims.

What is claimed is—

1. A machine for forming sheet-metal lath having dovetail channels therein, comprising upper and lower sets of dies, the upper dies being reciprocable into and out of seated relation to a sheet interposed between said sets and having rabbets presenting outwardly facing acute angles, and the lower dies being movable in upwardly and inwardly inclined directions into cooperative relation to said upper dies for pressing the metal of the sheet into said angles, means for automatically actuating said dies at definitely spaced intervals, and means for intermittently advancing the sheet.

2. A machine for forming sheet-metal lath having dovetail channels therein, comprising upper and lower sets of dies, the upper dies being normally elevated above the path of travel of a sheet between said sets, means for depressing said upper dies into seated relation to a sheet disposed in said path, said upper dies presenting outwardly facing acute angled channels, and the lower dies having portions adapted to substantially interfit with said channels, and means for actuating said lower dies in relatively inclined directions into and out of cooperative metal-shaping relation to said upper dies for pressing the metal of the sheet into said channels.

3. A machine for forming sheet-metal lath having dovetail channels therein, comprising a stationary element, means for in-

termittently advancing a metal sheet over said element, relatively shiftable companion dies reciprocable into and out of overlying seated relation to a sheet which overlies said element, said dies having therein longitudinal outwardly facing acute angled channels, and companion dies automatically shiftable in upwardly and inwardly inclined directions for pressing the metal of the sheet into the channels of the first mentioned dies.

4. A machine for forming sheet-metal lath having dovetail channels therein, comprising a stationary element, means for intermittently advancing a metal sheet over said element, relatively shiftable companion dies reciprocable into and out of overlying seated relation to a sheet which overlies said element, said dies having therein longitudinal outwardly facing acute angled channels, members slidable with respect to said stationary element, and operable through the latter in relatively inclined directions, a pair of lower dies carried by said members, and means for actuating said members for presenting said lower dies into cooperative relation to the depressed upper dies for pressing the metal of the interposed sheet into conforming relation to the channels of said upper dies.

5. A machine for forming sheet-metal lath having dovetail channels therein, comprising a stationary element, means for intermittently advancing a metal sheet over said element, relatively shiftable companion dies reciprocable into and out of overlying seated relation to a sheet which overlies said element, said dies having therein longitudinal outwardly facing acute angled channels, a pair of slides operable upon said stationary element in relatively inclined directions, lower dies carried by said slides, and automatic means for actuating said slides for carrying said dies into cooperative relation to the lowered upper dies for pressing the metal of the interposed sheet into conforming relation to said upper dies.

6. A machine for forming dovetail channels in metal sheets, comprising a turret of truncated cone form in cross section, a pair of upper dies reciprocable into seated relation to the portion of a sheet which overlies the top face of said turret, a pair of slides arranged for reciprocation over the inclined walls of said turret, lower dies carried by said slides shiftable with movements of the latter into cooperative sheet-bending relation to the seated upper dies, means for actuating said upper dies at spaced intervals, means for actuating said lower dies following seating of the upper dies, and means for advancing the sheet when both sets of dies occupy retracted positions.

7. A machine for forming dovetail channels in metal sheets, comprising a turret of

- truncated cone form in cross section, a pair of upper dies normally supported in an elevated position above the top of said turret, means for depressing said dies into seated relation to a metal sheet resting upon said turret, relatively inclined guideways formed on opposite sides of said turret, slides reciprocable in said guideways, lower dies carried by said slides adapted to be moved in upward shifting movements of the latter into cooperative sheet-shaping relation to the seated upper dies, and means for actuating said slides.
8. A machine for forming dovetail channels in metal sheets, comprising a turret of truncated cone form in cross section, a pair of upper dies normally supported in an elevated position above the top of said turret, means for depressing said dies into seated relation to a metal sheet resting upon said turret, relatively inclined guideways formed on opposite sides of said turret, a pair of slides shiftable in said guideways, lower dies carried by said slides, said lower dies being adapted to press the metal of an interposed sheet into conforming relation to said upper dies, means deflecting said lower dies inwardly in the final part of their shaping movement, and means for actuating said slides in timed relation to movements of the upper dies.
9. A machine for forming dovetail channels in metal sheets, comprising a turret of truncated cone form in cross section, a pair of upper dies normally supported in an elevated position above the top of said turret, means for depressing said dies into seated relation to a metal sheet resting upon said turret, relatively inclined guideways formed on opposite sides of said turret, a pair of slides shiftable in said guideways, lower dies carried by said slides, said lower dies being adapted to press the metal of an interposed sheet into conforming relation to said upper dies, means deflecting said lower dies inwardly in the final part of their shaping movement, and means for actuating said slides in timed relation to movements of the upper dies.
10. A machine for forming dovetail channels in metal sheets, comprising means for intermittently advancing a sheet, a pair of dies shiftable in relatively inclined directions below the path of travel of the sheets, a pair of upper dies normally supported elevated above said path of travel, and means for depressing said upper dies into seated relation to the underlying sheet, said upper dies having channels formed therein and said lower dies being movable into cooperative relation to the seated upper dies whereby the interposed sheet is pressed into the channels of the upper dies.
11. A machine for forming dovetail channels in metal sheets, comprising means for intermittently advancing a sheet, a pair of dies shiftable in relatively inclined directions below the path of travel of the sheets, a pair of upper dies normally supported elevated above said path of travel, means for depressing said upper dies into seated relation to the underlying sheet, said upper dies having channels formed therein, and said lower dies being movable into cooperative relation to the seated upper dies whereby the interposed sheet is pressed into the channels of the upper dies, said lower dies being actuated by pressure applied thereto through the descending upper dies.

In testimony whereof, I affix my signature.

JOSEPH R. McMAHON.
